(57) CLAIM

The ornamental design for a satchel, as shown and described.

DESCRIPTION

1.1 is a front, right perspective view of a first embodiment of a satchel showing our new design;

1.2 is a back, right perspective view thereof;

1.3 is a back view thereof;

1.4 is a front view thereof;

1.5 is a top view thereof;

1.6 is a bottom perspective view thereof;

1.7 is a right side view thereof; and

1.8 is a left side view thereof.

The broken lines depict environmental subject matter only and form no part of the claimed design.
